Specification for Design.

Patented May 24, 1921.

Application filed October 14, 1920. Serial No. 417,053. Term of patent 14 years.

To all whom it may concern:

Be it known that I, CHANDLER KING, a citizen of the United States, residing at Montgomery, in the county of Montgomery and the State of Alabama, have invented a new, original, and ornamental Design for a Bottle, of which the following is a specification, reference being had to the accompanying drawings, forming part thereof.

The figure is a side elevation of the bottle.

I claim:—

The ornamental design for a bottle as shown.

In testimony whereof I affix my signature.

CHANDLER KING.
